T. H. RODMAN,
CONTROLLER FOR POWER OPERATED DEVICES,
APPLICATION FILED MAR. 3, 1911.

1,251,286.

Patented Dec. 25, 1917.

UNITED STATES PATENT OFFICE.

THOMAS H. RODMAN, OF NEW YORK, N. Y., ASSIGNOR TO THE CUTLER-HAMMER MFG. CO., OF MILWAUKEE, WISCONSIN, A CORPORATION OF WISCONSIN.

CONTROLLER FOR POWER-OPERATED DEVICES.

1,251,286.

Specification of Letters Patent. Patented Dec. 25, 1917.

Application filed March 3, 1911. Serial No. 611,981.

To all whom it may concern:

Be it known that I, THOMAS H. RODMAN, a citizen of the United States, residing at New York, in the county of New York, and 5 State of New York, have invented new and useful Improvements in Controllers for Power-Operated Devices, of which the following is a full, clear, concise and exact description, reference being had to the accompanying drawing, forming a part of this specification.

My invention relates to improvements in controllers for power operated devices. It is particularly adapted for motor operated 15 printing presses, but is not limited in its application to this particular class of machinery.

In printing presses and many other devices operating upon runs or webs of paper 20 or other material it is necessary to be able to feed or thread the web through the mechanism at a relatively slow range of speed, commonly called the threading speed, and after the web is entirely threaded to 25 run the device at a relatively much higher range of speed which may be designated the operating speed. A break occurring in or any other interruption of the run or web while the device is at operating speed is 30 likely to cause serious injury to the machinery or waste of material before the trouble can be observed and the device brought to a stop.

It is one object of my invention to provide 35 an improved controller which will automatically stop a press or other device upon interruption of the supply of paper or other material fed therethrough, due to breakage thereof or from any other cause.

Another object of the invention is to provide 40 a controller, in connection with multiple speed devices, which automatically becomes effective to stop the device when predetermined conditions occur while the device is running at certain speeds but is ineffective to stop the device while it is running at other speeds.

A further object of my invention is to provide 45 means whereby after the press or other device has been stopped, it may be restarted at relatively slow or threading speed without regard to the position of the interruption detector, but may not be brought

up to operating speed until said detector has been restored to normal position.

Various other objects and advantages of my invention will be hereinafter clearly and fully set forth.

In order to more fully disclose the nature and characteristic features of my invention, 60 I shall describe the controller diagrammatically illustrated in the accompanying drawing, which embodies my invention in one form. It should be understood, however, that my invention is not limited to the 65 specific embodiment illustrated.

The controller illustrated is adapted for the control of a printing press providing the proper speed ranges by a two motor drive, one motor being used for slow or 70 threading speeds and the other for high or operating speeds. For the purpose of simplifying the drawing, I have omitted illustration of the press and have merely shown schematically a paper roll 1. For the purposes of this explanation, it may be assumed that the paper is run from the roll 1 over a small roll 2 directly into the machine and automatically fed into the machine 75 when it is in operation.

I have diagrammatically illustrated a small motor 3 for operating the press at slow or threading speeds and a large motor 4 for operating the press at normal operating or high speeds. These motors have 80 shunt field windings F and F' respectively connected in parallel directly across the supply lines L and L'. The armature circuits of the motors 3 and 4 are controlled by electroresponsive switches 5 and 6 respectively. The switch 6 has an auxiliary contact 7 adapted when said switch is open to bridge two stationary contacts for a purpose hereinafter set forth.

The operating windings of switches 5 and 95 6 have connected in series therewith respectively resistances 8 and 9 of such design as to prevent response of said switches, so long as they are in circuit therewith, but to allow sufficient current to traverse their 100 operating windings to maintain the same energized when they have once responded. Switches 10 and 11 are provided to short circuit the resistances 8 and 9 respectively. These switches are biased to open the short 105 circuits around their respective resistances,

but are arranged to be held in short circuiting position by latches 18 and 19 respectively. The latches 18 and 19 are arranged to be operated to release their respective switches upon response of the switches 5 and 6 respectively.

The speeds of the motors 3 and 4 are adapted to be regulated by a rheostat 20. As illustrated, this rheostat comprises a pivoted arm 21 having mounted thereon three electrically independent brushes 22, 23 and 24. The brush 22 is adapted to engage and to be moved over a series of contact segments 25. The brush 23 is adapted to engage a segment 26 and the brush 24 a segment 27. To a predetermined number of the contact segments 25 is connected a resistance 28 for the small motor 3. Connected to the remainder of the contact segments 25 is a resistance 29 for the large motor 4. The arm 21 of the rheostat is provided with lugs 30 and 31 adapted upon movement of said arm, to the position illustrated, to engage the short circuiting switches 10 and 11 to move the same into closed position in which position, they are automatically locked by their respective latching devices 18 and 19.

As will be hereinafter clearly set forth, the controller, as thus far described, is capable of being operated to start and stop and regulate the speed of the press at will.

I shall now describe the mechanism associated therewith to control the operation of the press automatically upon breakage, or other interruption of the supply of the paper fed into the press. This mechanism comprises a switch 33 located in close proximity to the paper fed into the press. Of course, the switch may be located at any desired point and any desired number thereof may be employed. The switch 33 comprises a bracket 34 adapted to be secured to any suitable part of the press and carrying stationary contacts 35 and a movable bridging contact 36. The contact 36 is carried by a bell crank lever 37 fulcrumed to the bracket 34. The bell crank lever 37 carries a roller 38 bearing upon the paper or web of the press. The parts of the switch 33 are so designed and adjusted as to remain in closed position so long as the paper or web of the press remains intact and to automatically open when the paper or web breaks or its supply is terminated or the tension therein becomes insufficient to hold the switch closed. The switch, as will be herein-after explained, is adapted upon opening to deenergize both switches 5 and 6 to stop both motors. When, however, the switch 6 opens, its auxiliary contact 7 short circuits the switch 33, thereby permitting the press to be restarted in the usual manner by the switch 5. So long, however, as the switch 33 remains open the press can only be operated

at slow or threading speed by the small motor 3.

I shall now describe the operation and functions of the controller assuming the switch 33 to be closed. To start the press the rheostat arm 21 is moved in a clockwise direction. It first engages contact segment 26 to complete the circuit of the operating winding of switch 5. This circuit may be traced from main line L to arm 21, through segment 26, conductor 40, switch 10, the operating winding of switch 5 and conductor 41, thence in parallel through conductor 42, switch 33 and conductor 43 and conductor 50 and switch 7, to conductor 44 and main line L'. Switch 5 thereupon responds, closing the armature circuit of motor 3 from main line L through rheostat arm 21 and resistance 28, conductor 45, switch 5, conductor 46 and through said motor armature to main line L'. The motor 3 thereupon starts setting the press in operation at slow speed. Continued movement of the arm 21 short-circuits the resistance 28 gradually increasing the speed of the motor 3 and in consequence the speed of the press through the threading speed range.

When all of the resistance 28 has been removed from circuit the arm 21 engages segment 27 to complete the circuit of the operating winding of switch 6. This circuit may be traced from main line L arm 21, contact segment 27, conductor 47, switch 11, the operating winding of switch 6, and thence in parallel through conductor 42, switch 33 and conductor 43, and conductor 50 and switch 7 to main line L' as already traced. Switch 6 thereupon responds closing the armature circuit of the large motor 4 from main line L arm 21 through all of the resistance 29, conductor 48 through said switch and through said motor armature to main line L'. The motor 4 thereupon starts to take up the drive of the press. Continued movement of the arm 21 gradually removes the resistance 29 to accelerate the motor and in consequence accelerate the press through the operating speed range. When moved a predetermined distance the arm 21 leaves the contact segment 26, thereby deenergizing the switch 5 and in consequence stopping the small motor.

As soon as the switches 5 and 6 respond they operate the latches 18 and 19 respectively to release the switches 10 and 11 respectively. This inserts the resistances 8 and 9 in series with the windings of switches 5 and 6 respectively. In consequence, if either motor switch is deenergized sufficiently to open it it cannot again be energized sufficiently to close it until the arm 21 is restored to initial position to reclose the short-circuiting switches 10 and 11.

To stop the press, it is only necessary to return the arm 21 to initial position, or if

desired, push buttons might be provided for deenergizing the switches 5 and 6 independently of the rheostat.

I shall now describe the functions of the switch 33. Ordinarily, there is little likelihood of the web or paper of the press breaking, except when the press is running at high or operating speed, or in other words, when driven by the large motor. If the paper did break while the press was operating at slow or threading speed, or in other words, when driven by the small motor, there would be no necessity for stopping the press. In fact when the web breaks it is necessary to run the press at a slow speed in order to again thread the web through. We will therefore assume for the sake of illustration, that the paper breaks while the press is operating at high speed after the small motor has been disconnected from circuit. In such an event the switch 33 would open. As has been previously seen, the switch 33 is included in circuit with the operating windings of both switches 5 and 6. In consequence, when the switch 33 opens, it deenergizes switch 6, which thereupon opens disconnecting the large motor 4 from circuit. The press therefore comes to rest. Further operation of the press can only be obtained by the return of the rheostat arm to initial position and then subsequent clockwise movement thereof. After the arm has been returned to initial position and then moved into engagement with segment 26, circuit will be closed through the operating winding of switch 5, as already described, to conductor 41. From this point with the switch 33 open and the auxiliary contact of switch 6 in the closed position illustrated, the circuit will continue by conductor 50 through the auxiliary contact 7 to conductor 44 and thence to the main line L'. Switch 5 will thereupon respond, again setting in operation the small motor and in consequence the press. This will enable the attendant to rethread the press without stopping to locate or reset the interruption or break detector. When the paper or web has been properly rethreaded through the press, the switch 33 will be automatically reclosed by the tension on the web, whereby, upon further movement of the rheostat arm, the switch 6 may be again closed and the large motor restarted to again bring the press up to full speed.

If an attempt should be made to bring the press up to full speed while the switch 33 was open, the result would be only momentary energization of the switch 6, inasmuch as upon responding it would immediately open its energizing circuit by raising its auxiliary contact 7. Thus, while the switch 33 is open, the press may be operated at slow speed by the motor 3, but cannot be operated by the large motor 4.

If the web should break during the period

both motors are operating, that is, while brushes 23 and 24 are simultaneously engaging segments 26 and 27 both switches 5 and 7 will be deenergized because their energizing circuits are then open at both switches 33 and 7. Both motors will thereupon be stopped and in order to restart the press the small motor must be started at its lower speed because switch 5 cannot be again closed until the resistance 8 has been short circuited by the return of switch 10 in a manner hereinbefore described.

Having thus described my invention, what I claim as new and desire to secure by Letters Patent is:

1. In a controller for power operated devices, in combination, means for starting the device and causing the same to operate at a slow speed or relatively high speed, and means associated therewith to cause said device to be automatically stopped upon the occurrence of predetermined conditions, said last mentioned means permitting restarting of the device to operate at slow speed, but preventing its operation at high speed so long as said conditions prevail.

2. In a controller for power operated devices, in combination, means for starting and stopping the device and regulating its speed between prescribed limits, and means associated therewith adapted under predetermined conditions to automatically cause the device to be stopped, said last mentioned means permitting restarting of the device while said conditions prevail, but restricting the effectiveness of said first mentioned means to vary the speed of the device.

3. In a controller for power operated devices, in combination, means for starting and varying the speed of the device between prescribed limits, and means associated therewith adapted upon occurrence of predetermined conditions to cause the device to be stopped and adapted until reset to permit restarting of the device, but to prevent the device from being accelerated beyond a predetermined degree.

4. In a controller for power operated devices, in combination, means for starting the device at will and regulating the speed thereof, and automatically operated means associated therewith to cause the device to be stopped under predetermined conditions and to restrict the effectiveness of said first mentioned means to vary the speed of the device.

5. In a controller for motor operated devices, in combination, two electroresponsive switches, one of said switches upon responding being adapted to cause the device to operate at a low speed and the other of said switches upon responding being adapted to cause the device to operate at a relatively high speed, and automatic means associated with said switches to deenergize

the same under predetermined conditions to stop the device, said first mentioned switch being adapted to be again energized while said conditions prevail, but said second mentioned switch being ineffective.

6. In a controller for power operated devices, in combination, an electroresponsive switch for causing the device to be operated at a slow speed, an electroresponsive switch for causing the device to be operated at a relatively high speed, a master switch for energizing said switches and means adapted to automatically operate under predetermined conditions to deenergize said second mentioned switch and to render said master switch ineffective to cause closure of said second mentioned switch so long as said conditions prevail, said first mentioned switch being always responsive to said master switch irrespective of said means.

7. In a controller for power operated devices, in combination, an electroresponsive switch adapted to cause the device to be operated at a slow speed, an electroresponsive switch adapted to cause the device to be operated at a relatively high speed, and means associated therewith adapted to automatically operate under predetermined conditions to deenergize both of said switches, said second mentioned switch upon being deenergized being adapted to establish a circuit for the operating winding of said first mentioned switch independent of said means whereby said first mentioned switch may be again energized while said conditions prevail.

8. In a controller for a device having a low speed motor and a relatively high speed motor for driving the same, in combination, means for controlling both motors at will and means adapted to automatically operate under predetermined conditions to cause both motors to be disconnected from circuit and to prevent subsequent operation of the high speed motor so long as said conditions prevail, said first mentioned means being effective to restart the low speed motor irrespective of said second mentioned means.

9. In a controller for power operated printing presses and the like, in combination, means for causing the press to be operated at a slow speed, or a relatively high speed, and a switch adapted to automatically operate upon breakage of the web of the press to cause the press to be stopped, said means being adapted to restart the motor prior to resetting of said switch, but said switch until reset restricting the speed of the press obtainable with said first mentioned means.

10. In a controller for printing presses having a plurality of operating motors for operating the same at different speeds, in combination, means for separately control-

ling the motors, and a switch adapted to automatically operate upon breakage of the web of the press to cause all of the driving motors to be stopped and until reset to permit restarting only of the motor for driving the press at slow speed.

11. In a controller for power-operated devices, in combination, two motors for operating the device at different speeds, successively operating controlling means for said motors, and mechanically controlled means for automatically stopping the operated device under certain conditions.

12. In a controller for power operated printing presses, in combination, electro-responsive control means for slow speed, electro-responsive control means for a higher speed, a switch responsive to breakage of the web of the press to deenergize said second mentioned means and until reset to prevent subsequent energization thereof and energizing connections for said first mentioned means independent of said switch.

13. In a controller for power driven printing presses, in combination, electro-responsive controlling means for slow speed, electro-responsive controlling means for a higher speed, a switch responsive to breakage of the web of the press to deenergize said second mentioned means and energizing connections for said first mentioned means independent of said switch but dependent upon predetermined positioning of said second mentioned means.

14. In combination, a printing press, a motor for driving the same at a relatively slow speed, a motor for driving said press at a relatively high speed, control means for said motors and a device governing said motor control means to stop said press upon breakage of the web, said device until reset insuring against operation of said press by said second mentioned motor but permitting restarting of said press and operation thereof by said first mentioned motor.

15. In combination, a printing press, a motor for driving the same at a slow speed, a motor for driving the same at a high speed and control means for said motors including a switch operable upon breakage of the web to stop said second motor and until reset to insure against restarting thereof and means for effecting operation of said first motor independently of said switch.

16. In combination, a printing press, a slow speed drive motor, a high speed drive motor, electro-responsive switches controlling the continuity of circuit of said motors, a paper-break switch and control circuits for said electro-responsive switches rendering energization of the switch of the high speed drive motor dependent upon said paper break switch and rendering the energization of the switch of said slow speed

drive motor independent of said paper break switch but dependent upon said other electroresponsive switch.

17. In a controller for power operated devices, the combination of means for operating the device at operating and threading speeds, and means for stopping the device under predetermined conditions only when said conditions occur while the device is being run at operating speed.

18. In a controller for power operated devices, the combination of means for operating the device at threading and operating speeds, means for stopping the device under predetermined conditions, and means rendering the stopping means ineffective when the conditions occur while the device is being run at threading speed.

19. In a controller for power operated devices, the combination of means for operating the device at threading and operating speeds, and means rendered operative to stop the device upon predetermined conditions arising while the device is being run at operating speed but not while it is being run at threading speed.

20. In a controller for power operated devices, the combination of means for operating the device at threading and operating speeds, means rendered operative to stop the device upon predetermined conditions arising while the device is being run at operating speed, but not while it is being run at threading speed, and means permitting the subsequent operation of said device at threading speed but not at operating speed while said conditions prevail.

21. A controller for power operated presses and similar devices adapted to act upon a web of material, comprising in combination means for driving the press at a web-threading speed and for thereafter driving the press at operating speeds, power switches for causing said means to drive the press at threading and operating speeds, and a switch affected by abnormal conditions occurring in the web only while the press is running at operating speeds to cause said power switches to affect said means to stop the press, preventing the running of the press at operating speeds as long as said abnormal conditions obtain and automatically acting upon the reestablishment of normal conditions in the web to allow said means to again drive the press at operating speeds.

22. A controller for power operated presses and similar devices adapted to act upon a web of material, comprising in combination means for driving the press at a web-threading speed and at operating speeds, a slow speed switch for controlling said means to drive the press at threading speed, a high speed switch for controlling said means to drive the press at operating speeds, a web-switch affected by abnormal

conditions in the web only while said means is under the control of the high speed switch to stop the press, and means under the control of the high speed switch for subsequently allowing the slow speed switch to cause the driving means to run the press at threading speed during the continuance of the abnormal conditions, said web-switch preventing the high speed switch from causing said driving means to run the press above threading speed so long as said abnormal conditions obtain.

23. In combination with a web press or similar device, driving means therefor capable of running the press at threading or operating speeds, a switch for controlling the supply of power to said means for driving at threading speed, a switch for controlling the supply of power to said means for driving at operating speed, a manually actuated controller for controlling both of said switches, a web-switch affected by abnormal conditions in the web to remove all power from said means to stop the press, and means under the control of said switches and said controller for preventing the subsequent starting of the press except at threading speed.

24. In a controller for power operated mechanism, motors for causing the mechanism to operate at different speeds, means for controlling the operation and speeds of the motors, and means for automatically stopping said mechanism under predetermined conditions and permitting it to be subsequently started and operated at slow speed only while the stopping conditions continue.

25. In a controller for power operated mechanism, motors for causing the mechanism to operate at different speeds, means for controlling the operation and speeds of the motors, and means for automatically stopping said mechanism under predetermined conditions and permitting said mechanism to be subsequently started and operated at threading speed under either the original or the changed conditions.

26. In a controller for power operated mechanism, motors for causing the mechanism to operate at different speeds, means for controlling the operation and speeds of the motors, and means for automatically stopping said mechanism under predetermined conditions and permitting said mechanism to be subsequently started and operated at threading speed under the initial or changed conditions and afterward at operating speed on the restoration of the original conditions.

27. In a controller for power operated mechanism, motors for causing the mechanism to operate at a slow speed or a relatively high speed, means for controlling the operation and speeds of the motors, and

means for automatically stopping said mechanism under predetermined changed conditions but permitting said mechanism to be subsequently started and operated at slow speed under all conditions and at high speed upon restoration of the initial conditions.

28. In a controller for power operated devices, in combination motors for causing the device to operate at a slow speed or a relatively high speed, means for controlling the operation and speeds of the motors, and means associated therewith to automatically stop the device under predetermined conditions, but to permit the device to be subsequently started and operated at a slow speed while such conditions prevail.

29. In a controller for power operated devices, in combination means for starting and stopping the device and regulating its speed between prescribed limits, and means associated therewith adapted under predetermined conditions to automatically cause the device to be stopped, said last mentioned means permitting restarting of the device while said conditions prevail but restricting the effectiveness of said first mentioned means to vary the speed of the device.

30. In a controller for power operated devices, in combination an electroresponsive switch for causing the device to be operated at a slow speed, an electroresponsive switch for causing the device to be operated at a relatively high speed, a master switch for energizing one or the other of said switches, and means adapted to automatically operate under predetermined conditions to deenergize one or both of said first mentioned switches and to render said master switch ineffective to cause closure of said second mentioned switch so long as said conditions prevail, said first mentioned switch being always responsive to said master switch irrespective of said means.

31. In a controller for power operated devices, in combination an electroresponsive switch adapted to cause the device to be operated at a slow speed, an electroresponsive switch adapted to cause the device to be operated at a relatively high speed, and means associated therewith adapted to automatically operate under predetermined conditions to deenergize both of said switches, the deenergization of said second mentioned switch leaving the device in condition for the establishment of a circuit for operating the first mentioned switch independently of said means, whereby said first mentioned switch may be again energized while said conditions prevail.

32. In a controller for a device having a slow speed motor and a relatively high speed motor for driving the same, in combination means for controlling both motors at will and means adapted to automatically operate under predetermined conditions to cause

both motors to be disconnected from circuit and to prevent subsequent operation of the high speed motor, so long as said conditions prevail, said first mentioned means being effective to restart the slow speed motor irrespective of said conditions.

33. In a controller for power operated printing presses and the like, in combination means for causing the press to be operated at a slow speed or a relatively high speed, and a switch adapted to automatically operate upon breakage or sagging of the web of the press to cause the press to be stopped, said means being adapted to restart the press, but said switch until reset restricting the speed of the press obtainable with said first mentioned means.

34. In a controller for printing presses having a plurality of operating motors for operating the same at different speeds, in combination means for separately controlling the motors, and a switch adapted to automatically operate upon breakage of the web of the press to cause all of the driving motors to be stopped, and when reset necessitating first the restarting of the motor for driving the press at slow speed before starting the motor for driving at high speed.

35. A controller for printing presses and the like having means for causing the press to operate at slow or comparatively high speed as desired, automatic means for stopping the operation of the press under certain conditions and preventing the operation of the press at high speed while said conditions continue, and means for causing the press to operate at slow speed while its operation at high speed is prevented.

36. A controller for printing presses and the like having means for causing the press to operate at different speeds, automatic means for discontinuing the operation of the press when predetermined conditions arise and when the press is operating at high speed, and means for causing the press to operate at lower speed while higher speed is prevented.

37. A controller for printing presses and the like provided with initially disconnected means for operating the press in different speed ranges, means for causing the press to be run in either speed range, and automatic means effective only when the press is running in a predetermined speed range for restoring the parts to initial positions.

38. A controller for printing presses and the like provided with means for operating the press in two ranges of speeds, devices controlling the operation at one range of speed, independent devices controlling the operation at the other range of speed, means for at will causing the press to operate in either range of speeds, and means brought into action in operating the press at only one range of speed, whereby undue deviation

of the web from its normal path at a certain point automatically stops the press and restores all parts to initial position.

39. The combination with a press provided with means for operating it at high speed and means for operating it at slow speed, of an electromagnet controlling the operation at high speed, an independent electromagnet controlling the operation at slow speed, devices under the operator's control for throwing either means into action, and means whereby undue deviation of the advancing web from its proper path during high speed operation automatically breaks the circuits of both magnets.

40. The combination with a press provided with means for operating it at high speed and means for operating it at slow speed, of an electromagnet controlling the operation at high speed, an electromagnet controlling the operation at slow speed, devices under the operator's control for throwing either means into action, and devices out of commission when the press is running at slow speed whereby at high speed of the press deviation of the web at a given point automatically cuts off the application of power to the press.

41. The combination with a press provided with means for operating it at high speed and means for operating it at slow speed, of an electromagnet controlling the operation at high speed, an electromagnet controlling the operation at slow speed, devices under the operator's control for throwing either means into action, devices out of commission when the press is running at slow speed whereby at high speed of the press deviation of the web at a given point automatically cuts off the application of power to the press, and means for preventing further application of power thereto without the intervention of an attendant.

42. The combination with a machine in which a web passes therethrough, of driving means therefor adapted to drive the machine at different speeds, and means to automatically stop the machine upon breakage of the web and prohibit operating the machine except at a threading speed until the web has again been re-threaded through the machine and brought under tension.

43. The combination with a printing press of driving means therefor, means for causing the press to be operated at different speeds, and means operating upon breakage of the web to stop the press and render it impossible to operate the press again at any other speed than the threading speed until the web has again been re-threaded through the press.

44. The combination with a machine through which a web passes, of driving means therefor to drive the machine at threading or operating speeds, and means to stop the machine automatically upon breakage of the web and preventing said machine being accelerated beyond threading speed until the web is re-threaded through the machine.

45. In combination with a machine in which a web passes therethrough, of means for driving the machine at operating and threading speeds, means rendered operable by the occurrence of abnormal conditions in the web for stopping the machine, and means for allowing the machine to be restarted only at threading speed during the continuance of the abnormal conditions.

46. The combination with a machine through which a web passes, of driving means therefor adapted to drive the machine at threading and at operating speeds, means to stop the machine automatically upon breakage of the web, and means preventing said machine from being accelerated beyond threading speed except upon the rethreading of the web.

47. In combination with a machine in which a web passes therethrough, of means for driving the machine at operating and threading speeds, means rendered operable by the breaking of the web for stopping the machine, and means for allowing the machine to be restarted only at threading speed before the web is rethreaded.

48. The combination with a machine through which a web passes of driving means therefor adapted to drive the machine at threading and at operating speeds, means to stop the machine automatically upon breakage of the web and necessitating the operation of the machine at threading speed before it can be run again at operating speed.

49. In a controller for power machines operating upon a web of material the combination of means for driving the machine at different speeds, means for controlling the speeds at which the machine is driven, means for automatically stopping the machine when the web breaks, and means permitting the machine to be restarted and run at threading speeds whether or not the web is rethreaded.

In witness whereof, I have hereunto subscribed my name in the presence of two witnesses.

THOMAS H. RODMAN.
